CLAIM

The ornamental design for a carbon dioxide compressing generator for dry ice manufacture, as shown and described.

DESCRIPTION

FIG. 1 is a top plan view of a carbon dioxide compressing generator for dry ice manufacture showing my new design;

FIG. 2 is a right side elevational view thereof;

FIG. 3 is a left side elevational view thereof;

FIG. 4 is a right end elevational view thereof;

FIG. 5 is a left end elevational view thereof;

FIG. 6 is a bottom plan view thereof; and

FIG. 7 is a top, right end and right side perspective view thereof.

FIG. 1

FIG. 2

FIG. 3

FIG. 6

FIG. 4

FIG. 5

FIG. 7
